UNITED STATES PATENT OFFICE.

WILLIAM G. HILSDORF, OF BROOKLYN, NEW YORK, ASSIGNOR TO JOHN H. WALTERS,
OF BROOKLYN, NEW YORK.

COUPON CUTTER.

Application filed July 10, 1920. Serial No. 395,369.

To all whom it may concern:

Be it known that I, WILLIAM G. HILSDORF, a citizen of the United States, and a resident of the borough of Brooklyn, in the city 5 of New York, county of Kings, and State of New York, have invented certain new and useful Improvements in Coupon Cutters, of which the following is a specification.

My invention relates to a machine for cutting coupons and an object thereof is the provision of a machine which may be either power-operated or operated by hand, which is adapted to cut a coupon from a plurality of bonds or the like simultaneously thereby 15 enabling coupons to be cut much more rapidly than is now possible, the present practice being to cut the coupons with a pair of scissors or the like.

In the accompanying drawings wherein I 20 have illustrated an embodiment of my invention,—

Fig. 1 shows my improved machine in front elevation;

Fig. 2 is a section taken on the line 2—2 25 of Fig. 1 in the direction of the arrows; and

Fig. 3 is a plan view of the apparatus of Figs. 1 and 2, showing the means which have been provided for adjusting the stationary knife employed in my machine.

Referring to the drawings in detail, 1 designates a base made of wood or other suitable material, this base constituting a receptacle for coupons after cutting, being 35 provided with a drawer 2 for receiving the coupons. It will be understood, of course, that if desired the coupons after cutting may be allowed to drop upon the table or other support upon which the base 1 is mounted 40 and in this event the drawer 2 would not be necessary.

The base 1 is provided with an opening 3 and two sides of this opening, to wit: the sides 4 and 5 are provided with a stationary knife 6, the cutting edges 7 and 8 of which are disposed at right angles to each other. This knife may be made in two pieces if desired but has been illustrated as being made in one piece. It is secured in place in the base 1 by means of a series of screws 9 which screws pass through a laterally extending flange 10 on the knife through slots 11 in this flange. These slots, as will be apparent from the drawings, are at right angles 55 to the front of the base 1 and together with

the screws 9 are provided for the purpose of permitting adjustment of the knife 6. This adjustment of the knife is obtained by operation of an adjusting screw or other device 12 extending through the front face of the base 1, its rear end engaging the knife so that when the screws 9 are loosened the screw 12 may be operated to cause the knife to be bodily moved in a direction away from the front face of the base 1. To facilitate proper movement of the knife 6 guides 13 have been provided. After the knife has been adjusted the screws 9 are set up and the knife will be maintained thereby in position. The base 1 carries a standard 14 extending vertically from the base and in this standard I have mounted guideways 15, these guideways receiving guides 16 and extending vertically relatively to the base 1. On the lower end of the guides 16 I mount a movable knife 17, this knife being provided with cutting faces 18 and 19 at right angles to each other, these cutting faces being adapted to cooperate with the cutting faces 7 and 8 of the knife 6. The upper ends 70 of the guides 16 project through the upper ends of the guideways 15 to be engaged by the surface of a rotatable cam 20, this cam being mounted in eccentric bearings 21 carried in the standard 14, the cam being rotated by means of a handle 22 as shown in the drawings but it is to be understood that if desired the cam may be rotated by power-driven mechanism. A coil spring 23 has its lower end secured to the knife 17 and its 80 upper end secured to the standard 14, this spring being provided for the purpose of retracting the knife 17 out of cutting position when the machine is in operation.

24 designates a number of bonds, for example, from which it is desired to cut the coupons 25. The bonds are moved into the position shown in the drawings and the handle 22 is then operated to cause the cam 20 to rotate in its eccentric bearings 21, this movement of the cam causing the guides 16 to be moved downwardly carrying with them the knife 17 thereby bringing the cutting edges 18 and 19 of this knife into operative relation to the cutting edges 7 and 8 of the stationary knife 6 to cut the coupons, this movement of the knife 17 at the same time placing the spring 23 under tension. The coupons as they are cut fall into the drawer 2. The handle 22 is then moved in the oppo- 110

site direction, carrying with it the cam 20 and the knife 17 is withdrawn to its initial or inoperative position by the spring 23. The knife 6 and the cutting portions of the 5 knife 17 may be removed for sharpening at any time that it may be desired and in order to compensate for the wear on the cutting edges 7 and 8 of the knife 6 I have provided the adjustment of this knife already referred 10 to and it will be understood that by providing this adjustment the two knives, to wit: knives 6 and 17, may always be adjusted to bring them into cutting or shearing relation.

15 What I claim is:

1. A coupon-cutter comprising in combination a base constituting a receptacle for cut coupons, a knife adjustably supported by said base and bodily movable thereon for 20 adjustment, said knife having two cutting faces or edges at an angle to each other, a standard mounted on said base, a second knife having two cutting edges or faces at right angles to each other, said last-named 25 knife being supported by said standard, guideways for said last-named knife in said standard, a cam for causing the last-named knife to move into position relative to the knife first mentioned to cut a coupon, and a

spring placed under tension by this movement of the knife to return the knife to its initial position. 30

2. A coupon-cutter comprising in combination a base, a knife mounted in said base and having two cutting edges disposed at 35 right angles to each other, a standard carried by said base, guideways therein, guides in said guideways, a knife having two cutting edges at right angles to each other carried by said guides, a rotatable cam 40 mounted in said standard and engaging said guides, means for rotating said cam, said cam when rotating moving said guides downwardly to move the knife carried thereby into operative position relatively to the first- 45 mentioned knife to cut a coupon, a drawer below the upper surface of the base for receiving the coupons so cut, and a spring, one end of which is secured to the knife carried by the guides and the other end of which is 50 secured to said standard for automatically moving the guides upwardly to retract the knife carried thereby to move the same out of cutting or operative position.

This specification signed this 28 day of 55 May, 1920.

WILLIAM G. HILSDORF.
